(57) **CLAIM**

The ornamental design for an electric appliance for food fermentation as shown and described.

DESCRIPTION

FIG. 1 is a front perspective view of an electric appliance for food fermentation.

FIG. 2 is an exploded view of the electric appliance for food fermentation shown in FIG. 1.

FIG. 3 is a top view of the electric appliance for food fermentation shown in FIG. 1.

FIG. 4 is a front view of the electric appliance for food fermentation shown in FIG. 1.

FIG. 5 is a rear view of the electric appliance for food fermentation shown in FIG. 1.

FIG. 6 is a left-side view of the electric appliance for food fermentation shown in FIG. 1; and,

FIG. 7 is a right-side view of the electric appliance for food fermentation shown in FIG. 1.

The broken lines show portions of the electric appliance for food fermentation and form no part of the claimed design.
